UNITED STATES PATENT OFFICE.

ERNEST LODGE WILSON, OF WEST CROYDON, ENGLAND.

CURTAIN-SUSPENSION DEVICE.

Application filed January 21, 1927, Serial No. 162,657, and in Great Britain January 26, 1926.

This invention relates to improvements in curtain suspension devices comprising runners, consisting of rollers provided with hooks or like fittings freely suspended from the rollers, and grooved or channelled tracks to provide upper and lower races in which the rollers run.

The object of the invention is to provide an improved device of this kind which can be economically manufactured, easily fitted up by unskilled persons, and will be efficient in use, the runners working easily without binding even if the curtain be pulled outwardly or inwardly as well as sideways.

15 A curtain suspension device according to the invention comprises a race having upper and lower channels and runners provided with disc rollers with rounded peripheries, which extend into both channels and have 20 a running engagement therein (i. e. a running clearance is provided), the channels being formed so that clearance is provided at the sides of the peripheries of the disc rollers to permit them to tilt in accordance with 25 the pull of the curtains, and so that the disc rollers which are guided between both channels, are prevented from leaving said channels and remain normal to the surfaces thereof irrespective of the direction of pull 30 on the curtains.

The race, is preferably formed of thin rolled, drawn or pressed metal, and with a rear web connecting the upper and lower channels, the web being punched or drilled 35 for screws or otherwise adapted for attachment to a window frame or other support. The web is preferably trough shaped or offset sufficiently to provide a recess for the heads of the screws so that they are clear 40 of the runners and to provide a section affording adequate strength.

In the accompanying drawings:—

Figure 1 is a cross sectional elevation showing on a very enlarged scale one form 45 of device according to the invention applied to a window frame.

Figure 2 is a front elevation of a similar form drawn on a less enlarged scale.

Figure 3 is a similar section to Figure 1 50 but showing a modified form of roller.

In the form of device illustrated a race is rolled or drawn in thin steel, brass or other metal with a cross section such as indicated in Figure 1, namely with upper and lower channelled portions 1, 1, connected by a rear

web 2, having holes punched or drilled in it at intervals for screws 3.

Each runner comprises a disc roller 4 freely mounted on a hanger arm, such as a wire 5 which is bent downwardly to form 60 a hook 6 for the attachment of the curtain. Washers 7 and 8 are mounted on the wire 5, one on each side of the disc roller 4, the washer 7 being forced tightly on to the wire and the end of the wire being riveted or 65 burred over to hold the washer 8 in position. Very slight clearance is left between the washers and the disc roller.

The disc roller 4 is slightly rounded on its periphery.

70 The inner surface of the channelled portions 1, 1, are curved to a radius which is the radius of the disc roller.

75 Clearance is left between the sides of the disc roller and a lip 9 and a ridge 10. By these means the disc roller which is guided between both channels is free to run properly without binding besides being prevented from leaving the channels, even if the runner be tilted due to the curtain being 80 pulled outwardly or inwardly as well as sideways, as the roller is always normal to the inner surface of the channels, it being understood of course, that a slight running clearance is provided for the disc roller.

85 The washer 7 and the wire 5 are shaped to avoid contact with the lower lip 9 in the event of the curtain being pulled inwardly.

If desired a disc roller such as indicated in Figure 3 may be used, having a boss 7' to 90 afford a long bearing to compensate for the omission of the washers.

95 The wire 5 may be bent into any desired form of hook 6 to receive a curtain hook 13, loop, ring or other device for attachment of the curtains.

100 The web 2 is preferably arranged as shown well back from the channelled portions so that ample clearance is left between the heads of the screws 3 and the disc roller.

105 The web may be made separate from the channelled portions which may be secured to a solid, perforated or other web or back portion which may be of metal, wood or other material, or they may be connected at intervals only by strips or wires provided with holes or loops or eyelets for the reception of the screws by which the race is to be secured to the window frame, brackets or other support.

110

Lengths of a race of the form illustrated may be set end to end and if desired the abutting ends may be enclosed in jointing pieces comprising thin metal sleeves shaped to correspond to the outer contour of the race and having holes corresponding to screw holes in the two parts of the race. Angular stop pieces as indicated at 11, Figure 2, may be screwed in position at each end. These may 10 be provided with hooks 12 to hold the ends of a curtain.

The race may be straight or be bent or curved to suit the shape of the window frame or other support to which it is to be attached, 15 or straight pieces may be united by specially curved pieces or elbows of the proper cross section.

I claim:

A curtain suspension device comprising a race formed of upper and lower channel members of arcuate cross section, and curtain runners each including a hanger arm and a roller of substantially similar radius as that of the channels to permit running engagement of the roller with the channels in various tilted positions of the roller, said channel members having outer lips and inner ridges to limit the tilting movements of the roller and prevent its separation from the race, the limited tilting movement of the roller preventing contact between the hanger arm and the channel members in any position of the roller. 20 25 30

In testimony whereof I have signed my name to this specification.

ERNEST LODGE WILSON.
